ELECTRICAL APPARATUS FOR COMPUTING A CHECK SYMBOL

Pierre Jacques Charles Chenus, Paris, France, assignor to Compagnie des Machines Bull (Societe Anonyme), Paris, France

Application June 14, 1951, Serial No. 231,540

Claims priority, application France June 15, 1950

5 Claims. (Cl. 235—61)

The present invention relates to calculating apparatus for effecting combinations in accordance with a given law so that said apparatus indicates at a given instant a certain result by a change in the condition of one of a group of output channels of the apparatus, and the energisation of one of a group of input channels of the apparatus results in a variation of the said change of condition from this output channel to another output channel as a function of the energised input channel and in accordance with the said law.

More specifically the broad object of the invention is to provide a calculating apparatus adapted to calculate from a number a checking symbol in terms of a base value N , the value of said checking symbol being equal to the difference between the sums of the digits of odd and even denominations of the number or to the complement to N of said difference. The calculating apparatus essentially comprises a digit entering device to successively enter in true value the digits of a number, two result storage devices under control of control means whereby a single storage device is alternately operative at each digit entry, electrical switching members and connections which are of the type of the so-called "column-shift arrangement," adapted in such a way that, when a digit is entered, the value of said entered digit is added to or subtracted from the value of the previously stored result according to which storage device was operative before said digit entry.

For a better understanding of the invention and to show how it may be carried into effect, the same will now be described with reference to the accompanying drawings, in which:

Figure 1 illustrates the principle of one form of the invention,

Figure 2 is a diagram corresponding to Figure 1,

Figures 3, 4 and 5 are similar diagrams corresponding to other forms of the invention,

Figure 6 is a diagram illustrating one embodiment of a calculating and checking apparatus according to a first embodiment,

Figure 7 is a diagram illustrating a calculating and checking apparatus according to a second embodiment,

Figure 8 shows a detail of Figure 6 illustrated in different form,

Figure 9 shows a third embodiment of a calculating and checking apparatus.

In accordance with the invention, it is proposed to provide apparatus comprising an assembly of members, preferably all identical and so disposed as to form a regular panel composed of a series of horizontal and vertical rows. Throughout the following description, members of an electrical nature connected by electrical connecting means will be considered, but it is to be understood that the invention is not limited to members of this type and that the said members may equally well be of magnetic, optical, hydraulic or other similar form, or of combined form, the connections made also being of corresponding nature. In addition, it is to be understood that when ref-

2

erence is made to an arrangement consisting of rows, or forming a panel, it is not the material position which is to be considered, but the mutual connections of the elements with one another and with the external elements acting thereon.

It will thus be assumed that a panel of members is provided in accordance with the invention as illustrated in Figure 1. One of these members is diagrammatically indicated at o , while the others are represented by dots for the sake of clarity of the drawing. There are thus n^2 members, the panel being assumed to be square but it would also be possible without departing from the scope of the invention to provide a rectangular panel comprising " $n \times p$ " members, " n " and " p " being different. In the left-hand part of the figure there are " n " input channels E_0 to E_n , corresponding respectively to the " n " horizontal rows and, at the top and bottom respectively, " n " terminals or input channels A_0 to A_n and B_0 to B_n . Each member o comprises three terminals or connections e , a , b and has the following property: If it is energised at a and at e it transmits energisation to b . Preferably, if it is energised at b and at e it conversely transmits energisation to a . This second property, however, is not essential and examples of embodiment of the invention will be shown in which it is not utilised. It will first be assumed that this property exists. The said members are readily conceivable and may vary considerably, that is, they may consist of relay controlled contacts, mechanical members or the like. The members o are, in accordance with the invention, connected to the terminals or input members E , A and B as indicated by the continuous lines, that is to say, all the members of one horizontal row of the order " x " may be energised from a common input member E_x , all the members of one vertical row of the order " z " may be energised from a common input member B_z or may transmit such energisation thereto, and all the members of one oblique row of the order " y " may be energised from a common input member A_y or may transmit such energisation thereto. It is to be noted that when a panel is formed of horizontal and vertical rows, various oblique rows are formed ipso facto, such as the two alignments which have been shown by way of example in chain lines extending from o , provided that they lead, if necessary by way of a deviation, to the input members at the top and bottom, these modifications being utilisable and also forming part of the invention. Starting with the arrangement shown in Figure 1, and assuming to begin with that the numbers $0, 1 \dots n$ of the different inputs correspond with one another, it will be seen that the simple relation:

$$x+y=z \quad (1)$$

is obtained for each member of the combining panel.

More especially, if $y=0$, there is obtained an energisation at B_x (chain line extending from A_0).

Conversely, the Relation 1 is written:

$$y=z-x \quad (2)$$

that is to say that if energisation is applied to E_x and to B_z an energisation is obtained at A_y . More especially, if $z=0$, y should be equal to $-x$. Obviously, supplementary inputs such as $A-x$ could be provided, but it is preferable according to the preferred embodiment of the invention, to consider that the terminals A and B form cyclic assemblies of base n , that is to say that the Relation 1 or 2 is accurate to within n . Thus, by applying an energisation to E_x and to B_0 , an energisation at A_{-x} will be obtained in the combining panel. Similarly, the extension (in dot-and-dash lines) of the diagonal of the order y issues at B_y .

It will be seen from the foregoing that a combining panel of the type shown in Figure 1 may be employed

to effect additions and subtractions. It may therefore be regarded as a calculating arrangement. As will be seen, in order to adapt the said arrangement to a suitable form in accordance with the preferred embodiments of the invention, it is necessary to add thereto at least some of the following auxiliary members:

Members for maintaining the energisation, imparting a momentary "memory" to the arrangement.

Members for cancelling out the preceding energisation for introducing a fresh energisation.

Utilisation members for storing, or indicating the voltages appearing at the output terminals of the arrangement, or for transmitting such voltages to a suitable counting or checking device.

Members for "setting" the panel prior to the introduction of an energisation.

Members for the total cancellation of the panel.

Members permitting the choosing of one of the following methods of operation: repeated additions, repeated subtractions, or alternate additions and subtractions.

Such an arrangement with these additions may be employed to effect in a convenient manner a series of alternate additions and subtractions of a series of numbers. As will be seen, when zero has been introduced into the apparatus in order to "set" it, the figures to be dealt with will be successively entered by impulses applied to the terminals E for the corresponding orders and the result will be obtained at any instant. It will therefore be seen that arrangements of this nature are particularly suitable for application to the calculating arrangements of the type referred to in United States patent applications of Knut Andreas Knutsen No. 190,507 of the 17th October, 1950, and No. 207,555 of the 24th January, 1951, and No. 216,887 of the 22nd March, 1951, apart from other applications.

Before proceeding with the description of the manner in which the invention is carried into effect, the possible modifications of calculating panels of this nature will be briefly indicated. Figure 1, may be diagrammatically illustrated as shown in Figure 2, in which the arrows indicate the increasing directions of the digits from A₀ to A_n, B₀ to B_n, and E₀ to E_n, and the diagonal of the square indicates the direction of the aforesaid oblique rows.

It may be noted that, if a digit "x" is to be added to a previously constituted result "y," a broken line may be followed in the direction A_y—O—B_x (Fig. 2) to obtain the new result z=y+x. Conversely if a digit "x" is to be subtracted from a previously constituted result "z," a similar broken line may be followed in the direction B_x—O—A_y to obtain the new result y=z-x.

The present invention effectively provides means adapted to automatically obtain that the entry of a number "x" in the calculating apparatus results in adding x when a result "y" is already stored therein, or in subtracting x when a result "z" is already stored therein. The continuation of entering operations results in a succession of alternate adding and subtracting operations.

Results z or y may assume values ranging from 0 to n-1, n being the base value considered. If it is desired to begin a series of operations with an addition, it is sufficient to first enter the value 0 in the storage device allotted to results "y"; if it is desired, as the case may be, to begin a series of operations with a subtraction, it is sufficient to first enter the value 0 in the storage device allotted to results "z."

On Fig. 2, the tracing of the broken line in the direction A_y—O—B_x may be represented by the formula:

$$z=y+x \quad (1)$$

The same tracing in a converse direction may be represented by the formula:

$$y=z-x \quad (2)$$

Other combinations may be adopted by replacing one

or two of the values x, y or z by their complement to the base value n.

By way of exemplification, Fig. 3 represents a theoretical diagram wherein x is replaced by n-x, the increasing values running from B₀ to A₀. The relevant formulas are:

$$z=y+n-x$$

for addition, and:

$$y=z-(n-x)$$

that is:

$$y=z-n+x$$

for subtraction.

In a similar manner, according to Fig. 4, the relevant formulas are:

$$n-z=y+x$$

that is:

$$z=n-y-x$$

for addition, and:

$$y=n-z-x$$

for subtraction.

According to Fig. 5, the corresponding formulas are:

$$n-z=y+n-x$$

that is:

$$z=x-y \quad (3)$$

for addition, and:

$$y=n-z-(n-x)$$

that is:

$$y=x-z \quad (4)$$

for subtraction.

It is easily seen (1) that various result values may be obtained simply by giving values complementary to n to the values x, y, or z; (2) the diagram according to Fig. 5 permits easily to calculate the difference between any entered digit lower than n and a previous result whatever may be the category y or z of the latter.

Assume x₁, x₂, x₃, x₄, etc., are the digits successively entered, and z₁, y₂, z₃, y₄, are the corresponding results: Formulas 3 and 4 allow one to build up the following table, assuming that, at the start, y=0.

	Entered digit	Results	according to Formula—
45			
z ₁		z ₁ =x ₁ -y=x ₁	(3)
x ₂		y ₂ =x ₂ -z ₁ =x ₂ -x ₁	(4)
x ₃		z ₃ =x ₃ -y ₂ =x ₃ -x ₂ +x ₁	(3)
x ₄		y ₄ =x ₄ -z ₃ =x ₄ -x ₃ +x ₂ -x ₁	(4)

For the purposes of the invention, the eventual carry-overs are discarded, since only values lower than n or in excess of n, or their complements to n, are significant.

Throughout the foregoing, it has been implicitly assumed, in order to facilitate the reasoning, that the digits entered into or delivered from the combining panel correspond to the indices of the letters. Thus, the digit 3 corresponds to E₃, A₃ and B₃. It is clear that this is by no means necessary and that it is possible to introduce an arbitrary correspondence—that is a code—between the indices of the letters and the digits, provided that the code is the same for the three entries. It will thus be possible to derive results from terminals which do not follow one another in the natural order of succession of the digits.

There will now be described by way of non-limitative example, with reference to Figure 6, a checking symbol calculating device established on the notation base 11, and applying the theoretical diagram of Fig. 5.

Figure 6 is composed of two figures, 6a and 6b, which actually constitute one single figure. It must be understood that the terminals indicated by chain lines in Figure 6b, A₀ to A_x and B₀ to B_x, are identical with the same terminals of Figure 6a.

There will be seen in Figure 6a movable contacts, E₀ to E_x which are either record, card reading, brushes, or

contacts closed by means of a keyboard or any other means.

Each contact energises an entry relay R_0 to R_X while each relay controls eleven contacts of a horizontal row of a circuit arrangement referred to as the combining panel. The upper terminals of the panel A_0 to A_X are connected respectively to upper storage relays MS_0 to MS_X , fitted with holding contacts CS_0 to CS_X . The lower terminals B_0 to B_X are connected to lower storage relays MI_0 to MIX , fitted with holding contacts CI_0 to CI_X . The upper and lower terminals are connected to unidirectional elements of the rectifier type, shown in Fig. 6b. These unidirectional elements are connected in pairs to the recording electromagnets F_0 to F_X on the one hand and to the indicating devices (lamps or the like) 0 to X on the other hand. The circuits of the recording electromagnets (which recording is effected by punching or printing record cards or in a like manner) are completed by the closing of the contact CE —and the indicating devices may be operated by closing of the contact CL . The unidirectional elements AS_0 and AB_0 are also shown in Figure 6a.

In addition, a trigger arrangement is employed to feed the combining panel alternatively through its upper terminals A_0 to A_X or through its lower terminals B_0 to B_X , so that the "symbol" may be automatically calculated by successive differences as digits are entered into the arrangement by depressing the keys E_0 to E_X . The principle of such a trigger arrangement will be understood more clearly with reference to Figure 8, which shows the essential parts thereof. The said arrangement comprises in symmetrical arrangement transformers TI or TS , the secondary winding of which feeds a relay RMI or RMS through a rectifier AI or AS , which loads a capacitor CI or CS at the terminals of the said relay. MIK is one of the relays MI_0 to MIX of Figure 6a, while MSK is one of the relays MS_0 to MS_X . I and S are utilisation arrangements, for example signalling arrangements. E is a key. Assuming first that the trigger arrangement is not energised and that a voltage is momentarily applied to J by the contact U , MSK is traversed by a current and CSK is closed. An impulse is set up through AI , RMI is energised and CMI opens momentarily, which has no effect at this instant. S therefore remains energised by CSK . If the contact U is opened again and E is momentarily depressed, there are obtained by an analogous process the closing of CIK , an impulse in AS , the momentary opening of CMS and consequently the breaking of MSK . Owing to the latter breaking, there is also an impulse at the secondary winding of TI , but it is of opposite sign to the preceding impulse and is stopped by AI . I then remains energised when E is raised. Each time that the key E is depressed again, U remaining henceforth open, inversion of the conditions of I and S will be obtained. A relay trigger arrangement is thus obtained which could also be employed to form "binary" impulse-counting chains, the carryovers of which are effected from J through the connection between an assembly of the type shown in Figure 8 and an analogous assembly.

Any other known trigger arrangement may be employed in the place of that just described and may be associated with the combining panel without departing from the scope of the invention.

In order to determine the symbol for checking a number "by eleven" with the aid of the arrangement according to the invention, the following procedure will be adopted:

According to the aforesaid patent application of the 17th October, 1950 the said symbol is so determined that the sum of the digits of even order of the number to be checked, including the symbol, is equal to the sum of the digits of uneven order, or the difference between these sums is null, or equal to 11, or 22, or another mul-

tiple of the checking base. In the example selected, the checking base is 11 for checking decimal numbers.

For example, consider the number 38420. Its symbol, as defined by the foregoing, is 8. According to the invention, the arrangement may be used in two ways. Either it serves to calculate the symbol, then this symbol is delivered at its output terminals; or the number 38420 is accompanied by its symbol already calculated, thus forming an "aggregate datum" (384208). In the latter case, the calculating arrangement is used to verify the transcription of the number.

The current is set up at the positive and negative terminals in Fig. 6a. When the current has been set up at these terminals, contact CD will be opened to ensure the resetting of the arrangement, and then re-closed. The storage relay MS_0 is energized from the positive terminal $+$, through contacts CD , CRD and the return to negative terminal $-$ is effected through windings PTI and RD .

As will be seen, at the start, the current passing through relay MS_0 , indicating a zero, also passes through the starting relay RD , which opens its contact CRD . Now, MS_0 is then only energized by its holding contact CS_0 . MS_0 being energized, the indicating device 0 may be fed through unidirectional element AS_0 , where key CL is closed. The first digit 3 is entered by depressing key E_3 , whereby entry relay R_3 is energized.

Since A_0 is energised; MI_3 is energised by the contact 33 and the terminal B_3 , and held by $C13$ so that 33 can be opened. An impulse in the relay R_3 is therefore sufficient for the value 3 to be introduced into the combining panel.

The circuit of MI_3 includes PTS which induces during the energisation of MI_3 an impulse in the trigger arrangement which temporarily opens CMS and breaks MS_0 . As CMI is closed, MI_3 remains energised and indicates 3 through AB_3 (Figure 6b) until the introduction of the following digit, which is 8.

The closing of E_8 energises R_8 which closes all the contacts of its horizontal row. B_8 is connected to A_5 by the contact 85 . The positive voltage thus applied energises MS_5 and, through TI , energises the relay RMI which breaks CMI and de-energises MI_3 .

At each digit entry, the automatic operation of the trigger device ensures the alternate setting into activity of the upper storage device (MS_0 - MS_X) and lower storage device (MI_0 - MIX). In course of the sequential introduction of the digits of the number 38,420, the operation of the apparatus may be summarized by the succession of the result relays at the registering condition, namely: MI_3 ; MS_5 ; MIX ; MS_3 ; MI_8 .

If it is desired to calculate the still unknown checking digit corresponding to said number, the operator closes the key CL and sees that this digit is an 8, as being manifested by the operativeness of the indicator device 8 , in parallel with relay MI_8 , through terminal B_8 and unidirectional element AB_8 .

If, on the other hand, it is desired to verify the correspondence of the checking digit with its associated number, after many eventual transcriptions on accounting documents, the succession of operations normally goes on with the final introduction of the read digit 8. As terminal B_8 is under voltage as soon as relay MI_8 is energized, it follows the energization of storage relay MS_0 , which manifests, through the resetting of the upper storage device, the searched correspondence. An error in the digits of the number or in the checking digit would cause the energization of a storage relay other than MS_0 , among MS_1 - MS_X , which would attract the operator's attention when he closes the key CL .

The apparatus may be included in or connected to a printing accounting machine. Upon closure of key CC (Fig. 6a), electromagnet EB may, for instance, serve to control the printing mechanism and cause it to print, on the document under check, a distinctive mark indi-

cating that no error was found during the checking process.

The Figure 7 shows a second embodiment of the invention in accordance with the diagram of Fig. 2 and established on the base value 10. It may be noted here that a checking digit or symbol calculated on base 10, nearly provides as good a security against errors as when calculated on base 11, on the condition that it also results from alternate additions and subtractions of the digits of the number handled.

The circuit Fig. 7 is substantially equivalent to that one shown by Fig. 6a, within the number of relays. Another relay trigger system is shown. The trigger essentially comprises electro-magnet RB1, relay I and cam controlled contact 74, the latter being provided to alternately set under voltage holding lines 70S and 70I. Such an alternation is effected at each energization of electro-magnet RB1.

In the conductors forming the connections of the relay contacts controlled by the entry relays R0-R9, there always is an incremental direction, that is from top left to bottom right. With respect to this direction, the digit entry relays R0-R9 are arranged in a normal order, as also are the storage relays MS0-MS9 and MI0-MI9.

The terminals A0-A9 and B0-B9 (Fig. 7) are respectively connected to the terminals with corresponding numbers A0-A9 and B0-B9 represented on Fig. 6b. This arrangement constitutes an application of the theoretical diagram of Fig. 2.

By way of example, the operation of the apparatus will be described, in relation to an illustrative number, namely, 7,561.

It is assumed that, before setting the apparatus under voltage, cam 75 and relay contacts 1a are in the positions shown by the drawing. Upon closure of key CD, relay I becomes energized, thereby transferring its contacts 1a and applying a positive voltage on holding line 70S. The subsequent closure of key contact D causes the energization of relay MS0, which holds itself energized through line 70S and its holding contact.

The first digit 7 is then introduced by the closing of contact E7. This causes the energization of relay R7 and electromagnet RB1. A circuit is completed from terminal A0, through one of the contacts controlled by R7, to terminal B7 and relay coil MI7. Upon energization of RB1 the pawl it controls is actuated and turns in a clockwise direction the ratchet wheel integral with cam 75, by a quarter of one revolution, thereby opening contact 74. Relay I being deenergized, contact 1a returns to the rest position. It is to be noted that the movable blade of contact 1a must be of such a size and form that the positive voltage be not removed from line 70S before line 70I is itself set under voltage. MS0 is thus de-energized while MI7 becomes energized and is held through its holding contact and line 70I. When contact E7 is released, RB1 obviously is de-energized and a spring moves back the pawl without changing the angular position of cam 75.

The introduction of the second digit 5 again causes the operation of the relay trigger which transfers contact 1a, thereby permitting the de-energization of relay MI7 and the held energization of relay MS2.

The whole operation may be summarized by the storage relays successively energized, namely: MI7, MS2, MI8, and MS7.

When the operator closes the key-contact CL (Fig. 6b) the indicator lamp 7 will be lighted, manifesting the value of the resulting symbol, that is 7, which is the difference between the digits of odd denominations ($7+6=13$) and even denominations ($5+1=6$).

According to another example, say the three-digit number 273, the operation of the arrangement according to Fig. 7 may be summarized by the succession of the storage relays sequentially energized, that is: MI2; MS5; and MI8.

When the operator closes the key-contact CL, the final energization of relay MI8 is accompanied by the lighting of indicator lamp 8. With respect to the difference between the sums of the digits of odd and even denominations, that is, $+2-7+3=-2$, the symbol 8 manifested is the complement to 10 of said difference, taking no account of the signs minus or plus.

Another embodiment of the invention will now be described with reference to Fig. 9. This embodiment is 10 designed to give the same results as those given by the circuits shown by Figs. 6a-6b and constitute also an application of the theoretical diagram of Fig. 5. In a manner similar to Fig. 6a, the values of the entry relays R0-RX and storage relays MIX-MI0 are allotted to said 15 relays in orders contrary to the incremental order resulting from the vertical and oblique connections. The base value is 11 and there is only one result storage device. A common relay G controls the setting under voltage of one holding line 100 and of one control line 101, by means 20 of three contacts G1, G2, G3, two of which (G1 and G3) being contacts with delayed actuation. The delay applies to closing as also to opening, and the delay of contact G1 is greater than that of contact G3.

Each storage relay controls a holding contact, C0 for 25 instance, and one delayed contact C0d, for instance. Push-button D controls the initial entry of 0 in the calculating apparatus. E0-EX are push-buttons, each of which has one normally closed contact and one normally opened contact, to control the entry of the digits to be 30 entered. Thanks to a spring action, all push-buttons return to normal position when released. Output terminals A0-AX are to be connected to the indicating organs shown by Fig. 6b, in accordance with corresponding values.

35 The operation is as follows. Let the symbol corresponding to the number 63 be calculated. The apparatus is set under voltage by closing key CD. Relay G becomes energized by a circuit extending from positive terminal +, through key contact CD, wire 103a, relay coil 40 G, wire 104, the closed contacts E0-EX in series, wires 102e, 102c, 102a, to negative terminal -. The momentary actuation of D completes two circuits. The first one extends from positive terminal +, through key contact CD, wire 103a, relay coil R0, wire 105, upper contact 45 D, wires 102d, 102c, 102a, to negative terminal -, thereby closing the horizontal row of contacts controlled by R0. The second one, through lower contact D, sets under voltage the wires 110a, 110b, 110c. It follows the energization of the storage relay MI0, which holds itself 50 energized through C0 and line 100. When push-button D is released, R0 is de-energized but terminal A0 remains under voltage, thanks to contact C0d closed.

The first digit 6 is entered by depressing push-button 55 E6, thereby breaking the energization circuit for relay G, and completing a circuit for relay R6, which closes its horizontal row of contacts. Contact G2 is immediately opened but contact G3 recloses a little later. During the time when contact G3 is not yet re-closed, line 100 is no longer under voltage and relay MI0 is de-energized. Due to the fact that the delay of G1 is greater than the delay of G3, terminal A0 remains under voltage a little time after re-closure of contact G3, permitting, during this time, the completion of a circuit extending from terminal +, through key contact CD, wires 103a, 60 103b, contact G1 still closed, line 101, contact C0d still closed, wires 110b, 110c, terminal A0, fifth contact from the left controlled by R6, terminal B6, relay coil MI6, wires 102b, 102a, to terminal -, energizing said relay. As soon as contact G1 is opened, said circuit is broken, 65 but relay MI6 holds itself energized through its contact C6 and line 100.

When push-button E6 is released, relay R6 is de-energized and relay G is energized again. As contact G3 is opened a little after contact G2 is closed, the holding circuit for relay MI6 is not broken. Still a little after, ter-

terminal A6 is set under voltage through G1 closed, line 101, contact C6d closed and wire 116.

Thereafter, the second digit 3 is entered, by depressing push-button E3. Relay R3 closes its contacts and relay G is de-energized. During the time when contact G3 is re-closed and contact G1 is not yet opened, the following circuit is completed: terminal +, key contact CD, wires 103a, 103b, contact G1 still closed, line 101, contact C6d still closed, wire 116, terminal A6, wire 106, third contact from the left controlled by R3, terminal B8, relay coil M18, wires 102b, 102a, to negative terminal -. After breaking of this circuit, relay M18 remains energized, and when E3 is released, terminal A8 remains under voltage, through wire 118 and contact C8d.

The indicating device 8 is now operative to display the symbol 8 corresponding to the number 63. As a matter of fact, in the aggregate datum 63 (8), $6+8-3=11$, which is in accordance with the required condition.

From the foregoing, it is readily seen that the last arrangement performs the operation: $z_i = x_i - z$, wherein x_i is the actually entered digit and z the previous result. In fact the operation rather is effected in form of: $z_i = x_i + n - z$, wherein $n=11$. When, according to the preceding example, 3 is entered after 6, $x_i=3$, $z=6$, $11-z=5$ and the operation is: $3+5=8$, giving the correct result.

It is recalled that the examples hereinbefore described are not intended in any way to limit the scope of the invention and that it is possible in addition to combine the features thereof in order to obtain a varied range of arrangements according to the invention.

I claim:

1. Electrical calculating apparatus for calculating from a number expressed in a numeration system of radix n a checking symbol in terms of a base value N and equal to the difference between the sum of the digits of the odd denominations and the sum of the digits of the even denominations of said number, or to the complement to N of said difference, comprising a digit entering device including a number n of entering relays, each assigned to introduce a distinct digit in the apparatus when operated, energizing means for selectively operating one of said entering relays, a first symbol storage device and a second symbol storage device comprising each a number N of storage relays, each relay either of said storage devices being assigned to one symbol value from 0 to $N-1$, control means made operative to control the successive operation of said first and second storage device alternately at each digit introduction in the apparatus, a circuit arrangement arranged as an addition table comprising a matrix of two-point make contacts with N columns and n rows, the contacts of each row being controlled by an associated one of said entering relays so that the contacts of one row are closed with a digit being introduced into the apparatus, a first group of conductors, a second group of conductors, each conductor of the first group connecting a distinct storage relay of the first storage device to contact points of all the rows, passing to a contact point of a different column for each different row, each conductor of the second group connecting a distinct storage relay of the second storage device to other contact points of a single column of said matrix so that with the first storage device operative and an entering relay operated to introduce a new digit, the latter is added without carry over to the value stored in said first storage device and the result is stored in said second storage device, and with the second storage device operative and an entering relay operated to introduce a new digit, the latter is subtracted without carry over from the value stored in said second storage device and the result is stored in said first storage device.

2. Electrical calculating apparatus as claimed in claim 1, wherein each of said storage relays has individual holding means, and including two holding lines each associated with one of said storage devices, and switching

means to set into activity at the start of operation a storage relay assigned to the 0 symbol in the first storage device, said control means cooperating with said storage devices, and controlling said holding lines so that each time an entering relay is made operative, a storage relay of one of said storage devices is selected for energization through a conductor of each of said group before the previously energized storage relay in the other of said storage devices is de-energized.

3. Electrical calculating apparatus as claimed in claim 1, wherein each of said storage relays has individual holding means for maintaining its energization, and including two holding lines each associated with one of said storage devices, and switching means to set into activity at the start of operations a storage relay assigned to the 0 symbol in said first storage device, said control means cooperating with said digit entering device, and controlling said holding lines so that whenever one of said entering relays is made operative, a storage relay of one of said storage devices is selected for energization through a conductor of each of said groups before the previously energized storage relay in the other of said storage devices is de-energized.

4. Electrical calculating apparatus for calculating from a number expressed in a numeration system of radix n a checking symbol in terms of a base value N and equal to the difference between the sums of the digits of odd and even denominations of said number, or to the complement to N of said difference, comprising a digit entering device including N entering relays, each assigned to introduce a distinct digit in the apparatus when operated, energizing means for selectively operating one of said entering relays, a first symbol storage device and a second symbol storage device, each comprising a number N of storage relays, each relay in either of said storage devices being assigned to one symbol value from 0 to $N-1$ and being fitted with individual holding means, two holding lines each associated with one of said storage devices, first switching means for making alive either of said holding lines, a circuit arrangement arranged as an addition table including a matrix of make contacts distributed in N columns and N contact rows, the contacts of each row being controlled by an associated one of said entering relays, so that the contacts of a different row will be closed according to which digit is being introduced in the apparatus, a first group of diagonal conductors in which group each conductor connects contacts pertaining to all the rows but to different columns of the matrix to a separate storage relay in said first storage device, a second group of conductors in which group each conductor connects the contacts of a single column to a separate storage relay in said second storage device, second switching means for energizing one storage relay of 0 value at the start of operation, control means for controlling said first switching means, said first and second storage devices cooperating with said control means so that each time an entering relay is energized, one storage relay in one storage device will be selected for energization through one conductor in both said groups in dependence on which storage relay was previously held energized in the other storage device and on which row of contacts is being closed.

5. Electrical calculating apparatus for calculating from a number expressed in a numeration system of radix n a checking symbol in terms of a base value N and equal to the difference between the sums of the digits of odd and even denominations of said number, or to the complement to N of said difference, comprising a digit entering device including N entering relays, each assigned to introduce a distinct digit in the apparatus when operated, energizing means for selectively operating one of said entering relays, a first symbol storage device and a second symbol storage device, each comprising a number N of storage relays, each relay in either of said storage devices being assigned to one symbol

value from 0 to $N-1$ and being fitted with individual holding means, two holding lines each associated with one of said storage devices, first switching means for making alive either of said holding lines, a circuit arrangement arranged as an addition table including a matrix of make contacts distributed in N columns and N contact rows, the contacts of each row being controlled by an associated one of said entering relays, so that the contacts of a different row will be closed according to which digit is being introduced in the apparatus, a first group of diagonal conductors in which group each conductor connects contacts pertaining to all the rows but to different columns of the matrix to a separate storage relay in said first storage device, a second group of conductors in which group each conductor connects the contacts of a single column to a separate storage relay in said second storage device, second switching means for energizing one storage relay of 0 value at the start of operation, control means for controlling said first switching means, said digit entering device cooperating with said control means so that each time an entering relay is energised, one storage relay in one storage device will be selected for energization through one conductor in both said groups in dependance on which

5

storage relay was previously held energized in the other storage device and on which row of contacts is being closed.
